COMBINED TOOTHBRUSH AND PASTE TUBE HOLDER

George A. Steece, Menlo Park, Calif.

Application November 8, 1954, Serial No. 33,004

Term of patent 14 years

(Cl. D4—3)

Fig. 1 is a perspective view of a combined toothbrush and paste tube holder, showing my new design.

Fig. 2 is an end elevational view of the far end of the holder of Fig. 1.

Fig. 3 is a top plan view of the holder of Fig. 1.

Fig. 4 is a front side elevational view of the holder of Fig. 1.

Fig. 5 is an end elevational view of the near end of the holder of Fig. 1.

I claim:

The ornamental design for a combined toothbrush and paste tube holder, as shown.
